(57) CLAIM

We claim the ornamental design for a guitar case, as shown and described.

DESCRIPTION

FIG. 1 is a perspective view showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing shoulder straps in FIG. 1 are understood to represent the portion of the design which forms no part of the claim. And the broken lines on the surface of the design throughout the views are understood to represent stitching.
